REEL

Henry J. Hogue, Lakewood, Ohio, assignor of
one-third to Charles L. Wasmer and one-third
to John C. Wasmer, both of Lakewood, Ohio

Application February 4, 1938, Serial No. 188,716

9 Claims. (Cl. 242—128)

This invention relates to reeling, and more particularly to a novel method and apparatus for continuously supplying wire or bar stock to a header or other fabricating machine from a bundle or coil of such stock.

5 An object of my invention is to provide a novel method of reeling by which successive coils of stock can be brought to the unwinding position and the leading end of each succeeding coil connected to the tail end of the preceding coil so that the stock can be supplied continuously and without interruption to a fabricating machine or the like.

10 Another object of my invention is to provide improved reeling apparatus for carrying out the method just referred to.

15 A further object of my invention is to provide an improved stock reel embodying a strand guiding means of novel arrangement and construction.

20 My invention may be further briefly summarized as consisting in certain novel steps of procedure, combinations and arrangements of parts hereinafter described and particularly set out in the appended claims.

25 In the accompanying sheets of drawings, Fig. 1 is a side elevation showing reeling apparatus constructed according to my invention and which may be used in carrying out my novel method;

30 Fig. 2 is a front view thereof looking in the direction indicated by line 2—2 of Fig. 1;

35 Fig. 3 is a vertical sectional view taken through the reel as indicated by line 3—3 of Fig. 2;

40 Fig. 4 is an enlarged partial sectional view taken through a portion of the mount for the rotatable strand guiding means, as indicated by line 4—4 of Fig. 2; and

45 Fig. 5 is a partial rear elevation looking toward a portion of the apparatus as indicated by line 5—5 of Fig. 4.

50 Further reference will now be made to the accompanying drawings for a more detailed description of my improved reeling apparatus and method, but it should be understood that my invention may be embodied in various other forms of similar apparatus, and that my reeling method can also be carried out with other apparatus than that herein disclosed.

55 My improved reeling apparatus, as shown in Figs. 1 and 2, may comprise a frame or mount 10 having rotatable strand guiding means 11 thereon, and a plurality of coil supports 12 and 12a which are adapted to be advanced, in succession, into an unwinding position adjacent the frame

whereby a continuous strand of bar or wire stock S can be unwound from the coils 13 and 13a and supplied to a header or other fabricating machine 15 without interruption. The supports 12 and 12a may be of any appropriate type or construction but are preferably vehicular in character and, without any limiting intent, may be conveniently referred to as "trucks."

60 An important feature of my invention provides for moving the truck 12 away from the unwinding position after unwinding of its coil, preferably though not necessarily by moving this truck past the frame 10 and in the direction of travel of the stock. As contemplated by my method, the truck 12a and its coil 13a may be moved to a position 15 adjacent the truck 12 and, while the coil 13 is being unwound, its tail end can be connected to the leading end of the coil 13a.

65 The frame 10 may be an upright or relatively inclined structure, formed of cast metal or other suitable material, and having a lower or base portion 16 adapted to rest on a foundation or on the floor 17 and an upper or ring portion 18 providing a mount for the rotatable strand guiding means 11. The ring portion may have a relatively large opening 18a in or adjacent which the strand guiding means may be mounted. The lower or base portion 16 may be constructed with laterally spaced legs 19 so as to provide the frame with an opening 20 of a height and width to permit the free passage of the coil-supporting trucks 12 and 12a in succession after their coils have been removed.

70 Each of the trucks may be in the nature of a low vehicle having a substantially flat body or platform 21 upon which the coil of stock may rest and a pair of wheels 22 at one or both ends to facilitate movement of the truck to and from the unwinding position in which the truck 12 is shown in Fig. 1. If desired, a pair of laterally spaced legs or brackets 23 may be provided at the rear end of each truck, in preference to wheels, so that the truck will have less tendency for accidental rolling or shifting away from the desired unwinding position. The body of the truck may have a transverse member 25 mounted thereon adjacent its forward end which is adapted to serve as a stop or retaining member to be engaged by the lower portion of the forward end of the coil 13 for retaining the latter in an upright or relatively inclined position as shown in Fig. 1.

75 Each truck may also be provided with an upright handle 26 which is preferably mounted adjacent the rear end of the truck and may be

formed by bending a pipe or bar to substantially the form shown in Fig. 2. The handle 26 may be mounted on the truck by having its ends received in openings or sockets 27 which may be located adjacent the rear end of the body 21. This handle facilitates the operation of moving the trucks to and from the unwinding position, and also serves as a rest against which the coil 13 may lean, as shown in Fig. 1. The handle 26 is removable from the truck 12, as by lifting out of the sockets 27, so that the truck can be moved through the frame opening 20 after the coil 13 has been unwound.

The strand guiding means 11, through which the stock S may be drawn while being unwound from the coil 13, may comprise a plate or spider 30 which is supported for relatively free rotation in front of the circular opening 18a of the ring portion 18 of the frame. The supporting means 20 for the spider 30 may comprise a plurality of grooved rollers 31 which are mounted on the ring portion 18 at circumferentially spaced points thereof and in which the beveled continuous outer edge or rim 32 of the spider engages. The rollers 31 may be mounted on the ring portion in various ways, for example, a suitable spindle-carrying bracket 34 may be provided for each roller and may be clamped against the ring portion by screws 35. Each roller may have a pair 30 of anti-friction bearings 36 therein for mounting it on the spindle 37 and may have suitable packings 38 for retaining lubricant in the bearings and excluding dust therefrom.

The rollers may be arranged in pairs, as shown in Fig. 2, with the brackets of the lower pair of rollers more or less permanently connected to the ring portion 18, and with the brackets for the upper pair of rollers having a detachable or adjustable connection with the ring portion to facilitate assembling the spider in place and for taking up wear or looseness. To provide for this adjustment of the brackets for the upper pair of rollers, the ring portion may have radially extending slots 39 and 40 through which the screws 35 and the spindle 37 extend, respectively, and may also have setscrews 41 which engage the spindle.

To facilitate passage of the stock S through the spider 30 I provide the latter with a sheave 43 or roller 43 which is adapted to be engaged by the stock. This roller may be mounted on the spider in any suitable manner, for example, it may be mounted on one of the arms 44 thereof and adjacent the outer rim portion 32.

For preventing the collapse and tangling of the convolutions of the coil 13 as the strand is pulled therefrom, I may provide a drum 45 which extends rearwardly from the spider 30 and into the center opening of the coil. This drum may be of hollow sheet metal construction, as shown in Fig. 3, and may be of tapered form and of a length to extend entirely through the coil. The drum is carried by the spider and is rotatably mounted so as to be free to turn independently of the spider and in either direction under the influence of the stock being unwound. For this purpose I provide a spindle 46 which is mounted in the central hub portion 47 of the spider, as by means of the pin 48, and extends rearwardly therefrom. The drum 45 may be mounted on the spindle 46 by means of longitudinally spaced anti-friction bearings 49 with which a central sleeve or hub 50 of the drum cooperates.

To facilitate the handling of the coils and the unwinding of the stock therefrom, it is desirable

to place the coils on the trucks so that they lean against the handles 26. In order to have the drum 45 enter the relatively inclined coil 13 when the latter is brought to the unwinding position, I prefer to arrange the drum so that its spindle 46 and rotation axis extend downward and rearward from the frame 10 at approximately the same angle as that at which the coil leans. In obtaining this inclined position for the drum, I find it desirable to construct the frame 10 so that it inclines rearwardly because this permits the drum to be mounted with its spindle and rotation axis extending rearwardly substantially normal to the plane in which the spider 30 of the stock guiding means operates.

In the operation of my improved reeling apparatus, the truck 12, having the coil 13 thereon, is moved to the unwinding position at the rear of the frame 10, with the drum 45 extending into or through the coil. As the stock is pulled from the coil 13 by the fabricating machine 15, it passes through the spider 30 in engagement with the roller or sheave 43, and, because of the eccentric position of this sheave with respect to the rotation axis of the spider, the stock causes the spider 25 to rotate in the mounting rollers 31. Any tendency for the convolutions of the coil to collapse or pull tight will result in such convolutions engaging the surface of the drum 45 and this will merely cause rotation of the drum whereby the 30 stock will be unwound without kinking or tangling thereof.

While the coil 13 is being unwound, a second truck 12a with a coil 13a thereon may be brought into position adjacent the truck 12 and the tail end 51 of the coil 13 may be connected with the leading end 52 of the coil 13a by a suitable weld 53. When the coil 13 has been used up or reduced to a relatively few convolutions, the handle 26 is removed and the empty truck 12 is then pushed through the frame opening 20 either as a separate operation or by the act of advancing the truck 12a and its coil 13a to the unwinding position. During the unwinding of the coil 13a, another truck with a coil thereon is brought to 45 the piston previously occupied by the truck 12a, and the operation of connecting the tail end of the coil with the leading end of the new coil is repeated. In this way, coil after coil can be conveniently brought to the reeling apparatus and 50 can be supplied to the fabricating machine 15 without interruption and without kinking of the stock.

From the foregoing description and accompanying drawings it will now be readily seen that I 55 have provided a novel reeling apparatus whereby coils of stock can be unwound in succession without kinking or tangling. It will also be seen that my apparatus and method provide for the passage of the empty trucks through an opening of the frame and the advancing of loaded trucks in succession to bring each succeeding coil to a position to be tucked onto the end of the coil being unwound, whereby a continuous supply of stock is made available and interruptions in the operation of a header or other fabricating machine are avoided.

While I have illustrated and described my improved reeling apparatus and method in a somewhat detailed manner, it should be understood that I do not wish to be limited to the exact arrangements of parts and steps of procedure herein disclosed, but regard my invention as including such changes and modifications as do not

constitute a departure from the spirit of the invention and the scope of the appended claims.

Having thus described my invention, I claim:

5. In apparatus of the character described, a frame, a vehicular support adapted to receive a coil of stock thereon and movable over a floor to a position adjacent the frame, and means rotatable on said frame on an axis substantially coaxial with the coil for guiding the stock being unwound from said coil, said frame having an arched portion providing adjacent the floor an opening of a size to permit passage of the vehicular support after unwinding of the coil.
10. In apparatus of the character described, a frame having rotary stock guiding means thereon, a rotatably mounted drum projecting from said frame with its rotation axis extending rearwardly and downwardly from the frame, and means for non-rotatably supporting a coil of stock in inclined relation with its convolutions surrounding the drum.
15. In apparatus of the character described, a frame, a member peripherally supported for rotation relative to the frame and having an eccentrically disposed stock-engaging roller thereon, a drum mounted for rotation with its axis extending rearwardly and downwardly relative to the frame, and means for non-rotatably supporting a coil of stock in inclined position with its convolutions surrounding said drum.
20. In apparatus of the character described, an upright frame inclined rearwardly from a vertical plane and having rotary stock guiding means thereon, a rotatably mounted tapered drum extending rearwardly and downwardly relative to the frame with its rotation axis substantially normal to the plane of said rotary guiding means, and means for non-rotatably supporting a coil of stock in rearwardly inclined relation with its convolutions surrounding the drum.
25. In apparatus of the character described, a frame, a rotatable member peripherally supported on said frame and having guide means engaged by the stock being unwound from a coil on the apparatus, the axis of rotation of said member extending in the general direction of movement of the stock from said coil, a drum carried by said member and relative to which said member is rotatable, and means for non-rotatably supporting a coil of stock so that it surrounds said drum, said frame and the coil supporting means

being such that the latter may be moved in the general direction of travel of the stock and past the frame after unwinding of said coil.

6. In apparatus of the character described, a frame having rotatable stock guiding means thereon and also having an opening adjacent the bottom thereof, and a support movable to a position adjacent the frame and adapted to non-rotatably support a coil of stock, said support having means against which the coil may lean, and which is removable to permit the support to pass through said opening.

7. In apparatus of the character described, a frame having rotatable stock guiding means thereon and also having an opening adjacent the bottom thereof, a support movable to a position adjacent the frame and being adapted to non-rotatably support a coil of stock, and a second support movable to a position adjacent the first support and adapted to non-rotatably support a second coil of stock in position for connection with the end of the first coil, said first support being movable through the frame opening after unwinding of its coil to permit the second support to be advanced with its coil.

8. The method of reeling which comprises moving a support with a coil thereon to an unwinding position adjacent a frame having stock guiding means thereon and an opening of a size to permit passage of said support, unwinding the coil by pulling the stock through said guiding means, and moving a second support with a coil thereon to the unwinding position and in the same operation pushing the first support through the frame opening.

9. The method of reeling which comprises moving a support with a coil thereon to an unwinding position adjacent a frame having stock guiding means thereon and an opening of a size to permit passage of said support, moving a second support with a coil thereon to a position adjacent the first support and connecting the tail end of the first coil to the leading end of the second coil, unwinding the first coil by pulling the stock through said guiding means, and moving the first support through the frame opening after unwinding of its coil and advancing the second support and its coil to the unwinding position.

HENRY J. HOGUE. 50
